CLAIM

The ornamental design for a paint roller cleaning device, as shown and described.

DESCRIPTION

FIG. 1 is a perspective view of a new design for a paint roller cleaning device;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines shown in FIGS. 2-3 depict portions of the article that form no part of the claimed design.

1 Claim, 6 Drawing Sheets
